US00D348000S

United States Patent [19]

Strasevicz et al.

[11] Patent Number: Des. 348,000

[45] Date of Patent: ** Jun. 21, 1994

[54] DISPLAY CARTON

[75] Inventors: **Steven A. Strasevicz, Yorba Linda; Robert Shoultz, Rancho Cucamonga, both of Calif.**

[73] Assignee: **Leucadia, Inc., New York, N.Y.**

[**] Term: **14 Years**

[21] Appl. No.: **951,413**

[22] Filed: **Sep. 25, 1992**

[52] U.S. Cl. **D9/415; D9/418**

[58] Field of Search .... **D9/415, 418, 432, 346, D9/341, 455, 337; 206/45.14, 45.31, 45.34, 44 R, 45.19, 301, 18, 70, 316.1, 320, 45.26, 45.31; 229/162, 164, 143, 169, 174, 147**

[57] CLAIM

The ornamental design for a display carton, as shown and described.

DESCRIPTION

FIG. 1 is a front elevational view of a display carton showing our new design;
 FIG. 2 is a left side elevational view thereof;
 FIG. 3 is a right side elevational view thereof;
 FIG. 4 is a top plan view thereof;
 FIG. 5 is a rear elevational view thereof; and,
 FIG. 6 is a bottom plan view thereof.
 The broken line showing of a top for a vanity in the display carton is for illustrative purposes only and forms no part of the claim.

FIG. 1

FIG. 2

FIG. 3

FIG. 4

FIG. 5

FIG. 6
